UNITED STATES PATENT OFFICE.

WILLIAM S. HUTCHINSON, OF OYSTER BAY, NEW YORK.

BRAKE.

1,192,316.

Specification of Letters Patent. Patented July 25, 1916.

Application filed August 4, 1915. Serial No. 43,692.

To all whom it may concern:

Be it known that I, WILLIAM S. HUTCHINSON, a citizen of the United States, and a resident of Oyster Bay, Nassau county, and 5 State of New York, have invented a new and useful Improvement in Brakes, of which the following is a full, clear, and exact description.

My invention relates to improvements in 10 brakes and especially to so-called drum brakes in which friction is applied to the inner surface of a rim, usually the rim on a drum which is carried by the hub of an automobile wheel, but obviously the brake 15 mechanism can be applied to any rotating rim which it is desired to control by a brake.

The object of my invention is to produce a very strong and simple means for locking a rotatable rim or member.

20 Another object of my invention is to apply the brake mechanism in such a manner that when the rim rotates in either direction and the inner shoe is in contact with the rim, the shoe will be automatically and 25 forcibly impinged against the rim.

Another object of my invention is to construct the mechanism so that the shoe will 30 always be in the right position for immediate and positive action and held in such a way that the shoe can be immediately locked or released.

Reference is to be had to the accompanying drawings forming a part of this specification, in which similar reference characters 35 indicate corresponding parts in all the views.

Figure 1 is an inside or end elevation of the mechanism embodying my invention as applied to the drum of automobiles. Fig. 40 2 is a cross section of the structure shown in Fig. 1, and Fig. 3 is a detail of a slightly modified form of the invention.

In the drawings 10 represents a rim to which it is desired to have the brake applied, 45 and this can be any rotatable member, though as illustrated and as usual, it is affixed to the drum 11, the latter being rigid on the wheel hub 12 which is carried as usual by the axle 13. The shoe 14 is arranged 50 within the rim 11 and movable back and forth in relation thereto, the shoe being preferably substantially concentric with the rim and having its ends adjacent and connected by a spring 15. Mechanism 16 is used 55 for opening and closing the shoe, that is for bringing it into frictional engagement

with the rim 11, and removing it from such frictional engagement. When the rim 11 is rotating and the shoe is in frictional engagement therewith, the parts are automatically 60 locked, as will be presently described.

At necessary intervals on the inner part of the shoe 14 are lever blocks 17 which are pivoted as shown at 18 to the members 19 which clamp the strengthening rib 14^a of the 65 shoe, but these members 17 can be pivoted to the shoe in any convenient manner. Each lever block 17 is preferably of a generally triangular shape, though the shape is not essential, and on its inner face it has a plurality of seats 20 opening inwardly and adapted to seat upon the studs 21 which are spaced apart and have a stationary position with reference to the rotating rim 11. These studs can be supported in any convenient way, and as shown are carried by the 70 end plate 22 which covers the open end of the drum 11, and is secured to the housing 23 on the axle 13.

It will be seen that when the shoe 14 is 80 in frictional engagement with the rim 11 and the latter is moved in either direction, the blocks 17 acting as levers, will oscillate, and one of the studs 21 of each block will serve as a fulcrum so that the shoe is forced 85 strongly against the rim 11. If the rim moves in the opposite direction, the same action takes place except that each block oscillates on the second pin, which in this case serves as a fulcrum. 90

It will be noticed that the pins 21 and blocks 17 serve to position the shoe 14 with relation to the rim, and further that the essential thing is to have the studs or abutments 21 stationary, while the members 17 95 are pivotally connected with the shoe. It is not essential that they be connected in the exact manner shown, but they should have a pivotal connection so as to adapt themselves to the movement of the shoe and to 100 rock on their respective fulcrums 21 when the shoe is moved with the rim 11 in either direction.

It is obvious that the block 17 can be adapted to rock on its two fulcrums even 105 though said fulcrums are not stationary. For instance as shown in Fig. 3, the block 17^a can be provided with ball-shaped terminals 17^b which fit in the socket 17^c of a casting 22^a and this can be for instance a part 110 of the part 22 on any stationary support. It will be seen that the action is the same

and that the block 17^a will rock first on one ball 17^b and then on the other, while the socket serves to keep the block in proper relation to other parts of the structure.

5 I claim:—

1. A brake comprising a rotatable member, a shoe arranged within said member and movable back and forth in relation thereto, a lever block pivotally connected 10 with the back of the shoe, and stationary abutments between the lever block and the axis of the rotatable member, said lever block seating and rocking upon said abutments.
- 15 2. A brake comprising a rotatable member a shoe essentially concentric with and lying within said rotatable member, the shoe having a limited rotary movement with said rotatable member, a plurality of oscillating 20 blocks pivotally connected with the shoe, and a plurality of abutments for each block upon which the block seats and rocks, said abutments being located between the shoe and the axis of the rotatable member.
- 25 3. A brake comprising a rotatable mem-

ber, a shoe arranged within the member and movable into and out of frictional engagement with said member, said shoe also having a limited rotary movement in both directions with said rotatable member, a plurality of blocks pivoted to the back of the shoe, and each provided with seats spaced apart, and abutments for said block seats, said abutments being located between the shoe and the axis of the rotatable member. 30

4. A brake comprising a rotatable member, an expansible shoe arranged within the member and essentially concentric therewith, said shoe having a limited rotary movement with said rotatable member, a 40 plurality of blocks pivoted to the back of the shoe, and stationary abutments for each block, said abutments being spaced apart and serving as fulcrums for the oscillating block. 35
